E. N. LODGE

MOUNTING FOR PHOTOGRAPHS

Filed Oct. 9, 1923

Inventor,
Edward N. Lodge,
Frank S. Caleman
Attorney

UNITED STATES PATENT OFFICE.

EDWARD N. LODGE, OF COLUMBUS, OHIO.

MOUNTING FOR PHOTOGRAPHS.

Application filed October 9, 1923. Serial No. 667,534.

To all whom it may concern:

Be it known that I, EDWARD N. LODGE, a citizen of the United States of America, and resident of Columbus, in the county of 5 Franklin and State of Ohio, have invented certain new and useful Improvements in Mountings for Photographs, of which the following is a specification.

This invention relates to photographic 10 mountings or folders, and particularly to a mounting including flaps which overlie the front of the picture or photograph when in a folded state, the said flaps being capable of adjustment with relation to the back of the 15 mounting in order that the mounting will stand alone, or without any easel or other support than that provided by the improvements forming part of this invention.

It is an object of this invention to produce 20 a mounting comprising a back and flaps, the material of which is of such rigidity as to stand on end or edge when the portions thereof have been properly manipulated to bring them into such positions with relation 25 to one another as to cause them to be self-supporting in an upright position; and it is furthermore an object of this invention to produce a device of the character indicated, having the characteristics stated without 30 increasing the dimensions of mountings comprising backs and flaps such as are now commonly used for mounting photographs.

It is furthermore an object of this invention to produce a photograph mounting 35 which can be cut and shaped at a single operation of the cutting or stamping machine, thus making it possible to produce the results of the invention without adding to the cost of the material, or to the cost of manufacturing.

With the foregoing and other objects in view, the invention consists in the details of construction, and in the arrangement and combination of parts to be hereinafter more 45 fully set forth and claimed.

In describing the invention in detail, reference will be had to the accompanying drawings forming part of this application wherein like characters denote corresponding 50 parts in the several views, and in which—

Figure 1 illustrates a view in perspective of a photograph mounting embodying the invention;

55 Figure 2 illustrates a view in elevation thereof with the folders closed;

Figure 3 illustrates a top plan view of the edge of the mounting;

Figure 4 illustrates a similar view with the flaps in different positions of adjustment;

Figure 5 illustrates a similar view showing a further modification with respect to the adjustment of the flaps;

Figure 6 illustrates an enlarged horizontal 65 sectional view of a fragment of the mounting; and

Figure 7 illustrates a top plan view of the edge of the mounting in different shape.

In these drawings, 10 denotes what may 70 be termed the back of the mounting or folder, having integral flaps 11 and 12 at the side edges thereof, the said mounting being scored or provided with creases 13 and 14 at the junctions of the back 10 and the 75 flaps 11 and 12 respectively. The flaps are also creased or scored longitudinally or vertically as shown at 15, although this scoring does not prevent the flaps from being folded, one over the other, to overlie the photograph 80 and protect it.

The flaps are capable of being adjusted to different angles with respect to the back, and those sections of the flaps beyond the 85 creases or folds 15 can likewise be adjusted to different positions or angles with respect to the back, and with respect to those portions of the flaps between the creases 15 and the back, thus making it possible to cause the mounting or folder to stand on edge 90 without supplemental supports, as shown in Figs. 1, 3, 4 and 5.

As illustrated, the portions of the flaps between the folds 13, 14 and 15 can be extended rearwardly of the flaps, and those 95 portions of the flaps beyond the creases 15 may likewise be adjusted to different angles, this last mentioned expedient serving to leave the photograph or picture wholly exposed from practically any angle in advance of the picture and prevent the casting of shadows thereon.

The mountings of this character are usually made of relatively heavy fibre or cardboard, and if the creases are properly 105 made, or if the paper is properly scored, the flaps will retain their adjustments without the employment of fastenings or the like.

Associated with the mounting or folder, there is provided a photograph securing or 110 holding member A which may be secured to the back of the folder in appropriate man-

2
ner as by adhesive. The photograph holder occupies the area or approximately the area between the creases 13 and 14 with sufficient space between the edges of the photograph holder and the creases to permit the flaps to assume the different positions illustrated. For instance, in Figure 5 where the flaps are folded inwardly on the creases 13 and 14 the clearances between the edge of the photograph mounting and the creases permit the manipulation of the device to be accomplished without the flaps encountering the edges of the photograph holder.

10 I claim:
15 A mounting for photographs comprising a back on which the photograph is mounted,

integral flaps creased at the junction of the back and flaps whereby the said flaps can be folded across the mounted photograph to protect it, the said flaps being creased in a line parallel with the creases between the back and the flaps whereby one portion of each flap may be bent at an angle to another portion thereof, and with relation to the back, the said creases being effective to decrease the flexibility of the joints between the sections of flaps and between the flaps and the back to cause them to retain positions of adjustment for the purpose described.

20 25
EDWARD N. LODGE.
